Primary Examiner — Rashida C. Walshon(74) *Attorney, Agent, or Firm* — BERESKIN & PARR LLP/S.E.N.C.R.L., s.r.l.(57) **CLAIM**

The ornamental design for a boot, as shown and described.

DESCRIPTION

FIG. 1 is a top perspective view of a boot showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Portions of the boot illustrated in darker broken lines in FIGS. 1-8 represent stitching. Portions of the boot illustrated in stippled lines form no part of the claimed design.

1 Claim, 8 Drawing Sheets(56)
